ELECTRIC SIGNALING.

1,281,684.

Specification of Letters Patent. Patented Oct. 15, 1918.

Application filed August 14, 1916. Serial No. 114,824.

To all whom it may concern:

Be it known that we, GEORGE OWEN SQUIER, lieutenant col., U. S. Army, LOUIS W. AUSTIN, and LOUIS COHEN, all residing at Washington, in the District of Columbia, have invented certain new and useful Improvements in Electric Signaling, of which the following is a specification.

This invention relates to electrical signaling, in which the messages are transmitted by unbroken alternating currents, the amplitude of whose waves is varied to produce the signaling impulses, as first described in British Letters Patent No. 22,265, issued Nov. 19, 1914, upon the invention of George Owen Squier.

The present invention has for its object, to increase the working capacity of the Squier standard duplex system, and consists in superimposing upon this standard duplex system, an extra simplex circuit equipped at one end with a sending and at its other end with a receiving instrument, and in which messages are transmitted by unbroken alternating current of a frequency different from that employed in the duplex system, and interpreted by the ear; this interpretation, where the frequency of the simplex system requires it, being through the medium of an oscillating audion system or ticker arrangement, operatively connected to an oscillating circuit which is linked electromagnetically with the cable, or interpreted directly in said telephone, where the frequency of the signaling current is well within audition. In other words, the frequencies of the standard duplex system and the superimposed simplex circuit may both be below audition, the latter being brought within audition by some suitable instrumentality at the receiving end; or the former may be below audition and the latter well within audition, in which case the current of the simplex circuit can be interpreted directly in a telephone without the interposition of the other instrumentalities.

The sending current of each system is rendered ineffective in the receiving equipment of the other system as by counterbalancing 50 transformers at the transmitting end of the simplex system and by electrical tuning at the receiving end of the simplex system and by having the transmitted current of the simplex system insufficient to affect the receiver at the remote end of the duplex sys-

tem, but sufficient to operate the more sensitive receiving instruments employed in the simplex system at that end.

Three illustrative embodiments of the invention, differing mainly in the circuit arrangements and devices employed for the superimposed system are shown schematically in the accompanying drawings and designated respectively as Figures 1, 2 and 3.

In each of the figures, A and B represent two stations at opposite ends of the duplex electrical signaling system, such for instance, as the ends of an inter-continental cable system, and in each of these figures, the duplex system is substantially identical in principle with that described in British Letters Patent No. 22,265 of 1914, already referred to; that is to say, at each end of the duplex system, 1 represents a source of alternating current, 2, 3, the coils of the transformer by which said current is impressed upon the line, the primary of which includes a suitable device 4, for varying the amplitude of the waves of such current and the secondary of which is grounded at 5. 6 represents balancing condensers, 7 the receiving device, and 8 the artificial cable. These instrumentalities are duplicated at the ends of the cable 9, and constitute the standard equipment of a duplex system in accordance with said British patent.

The present invention increases the working capacity of a cable or other telegraph system, having the above-described duplex equipment, by superimposing upon the line, 90 an extra simplex system which may consist of the following instrumentalities:

10 represents a source of alternating current in the primary circuit of a transformer 11, 12, which primary circuit also includes a 95 device 13, for varying the amplitude of the waves of said current, while the secondary coil 12, is included in the circuit of cable 9. The source 10, will be operated to produce a frequency that is higher than that of the source 1, so that at the opposite end of the system, distinct signals transmitted through the medium of these two currents may be separately received.

In order to prevent the current from the 105 source 10, affecting the receiving device 7, an additional balancing transformer 14, 15, is introduced between the circuit of source 10 and the circuit of receiving device 7; this transformer being so related to the trans- 110

former 11, 12, that E. M. F.'s of opposite phase are generated in the circuit of the receiving device 7, and they are so adjusted as to balance each other in regard to the intensities of the E. M. F.'s induced in the circuit of receiver 7.

As a further safe-guard against disturbing influences in the receiving-device circuit, from the source 10, a loop circuit is employed consisting of the capacity 16 and inductance 17, connected in parallel, and tuned to be in resonance for the frequency of source 10, thereby offering a great resistance to any residual current from source 10, which may be due to lack of perfect balance. A sending equipment for an extra simplex circuit is hereby created, capable of impressing an alternating current on the cable 9, without affecting the receiving device 7 at the corresponding end of the duplex system, or in any way interfering with the operation of the duplex system at that end.

The receiving equipment of the superimposed simplex circuit, located at the station B, will consist, according to Fig. 1, in the transformer 18, 19, of which the primary 18, is in the cable circuit, while the secondary coil 19 is in circuit with tuning condenser 20 and telephone 21.

At the receiving end B of the simplex system, which is a sending as well as a receiving end of the duplex system, means must be employed for preventing current from source 1 from acting through the transformer 18, 19, upon the telephone 21. To this end, an additional transformer 22, 23, is introduced with its primary 22 in series with the artificial cable 8, at station B, and its secondary 23 in the circuit of telephone 21. The transformer 22, 23, is so connected as to induce an E. M. F. opposite in phase to that induced by transformer 18, 19, and since the current from local source 1 in primary 18 which is in the cable circuit and the current from the same source in the artificial cable 8 are exactly the same, the effect of local source 1 acting through transformer 18, 19 upon the circuit of telephone 21 will be neutralized.

In the embodiment of the invention just described, in accordance with Fig. 1, the frequency of source 10 of the superimposed simplex system must be within audition so that it can be heard directly in the telephone 21. Current from source 1, of station A will not affect the telephone 21, first because it is of a frequency below audition and secondly, because the circuit of telephone 21 is tuned to be in resonance for the frequency of source 10 and thus offers great impedance to incoming current transmitted by source 1. Furthermore, current from source 10 will be of too small magnitude to affect receiving device 7, at station B, which is of much less sensitiveness as compared with telephone

21; moreover, receiving instrument 7, being of a nature to interpret signals of the duplex system visually, would not respond to the high frequency of the source 10.

The embodiment shown in Fig. 2 is similar to that shown in Fig. 1, in general arrangement, and so far as concerns the use of a frequency for the superimposed simplex system, which is within audition and therefore received directly in the telephone 21. But according to Fig. 2, the receiving instrument 7 at station A, instead of being connected directly across the balancing condensers 6, 6, of the duplex equipment, is connected in an independent circuit which is coupled therewith, through means of the transformer 24, 25; said independent circuit including the secondary coil 25 of said transformer together with the loop circuit 16, 17, and receiving device 7. Then, to counterbalance the effect of current from source 10 upon the receiving device 7, a counterbalance effect is produced between the circuit of source 10 and the secondary circuit which includes receiver 7, by means of a double transformer 14^a, 15^a, and 14^b, 15^b.

Double transformation is necessary because of the double transformation through which source 10 affects the circuit of receiver 7 when acting through transformers 11, 12, and 24, 25. These double transformations on both sides make it possible to adjust the E. M. F.'s acting upon the circuit of receiver 7 so that they will be exactly opposed in phase and it will only be necessary to adjust them for equality in induced E. M. F., in order to neutralize their effects upon the receiver 7.

Fig. 3 is designed to illustrate a modification at the receiving end of the superimposed simplex system. For convenience, it is based upon the arrangement of Fig. 1, but the modification is equally applicable to a superimposed simplex system having the sending equipment illustrated in Fig. 2. According to Fig. 3, the frequency of the source 10 of the simplex system is either wholly below audition or not clearly within audition, so that it can not be directly interpreted in the telephones, and thus requires a device at the receiving end of the simplex system to render it directly audible. Different instrumentalities may be employed for this purpose, such for instance, as the oscillating audion or the ticker, described in the co-pending application Serial No. 114,808 filed by two of the applicants of this case, namely, Messrs. Austin and Cohen. 27, in Fig. 3, represents such a device, capable of modifying an alternating current of frequency that is below audition and rendering it audible.

That is to say, 27, represents either a ticker or an audion introduced in the receiving circuit of the superimposed simplex sys-

tem, according to the arrangement of Messrs. Austin and Cohen in which 19, 20, 23 represent an oscillating circuit, 21, the telephone and 21, 26, 27, the receiver circuit 5 proper, which is connected with said oscillating circuit.

During the operation of the duplex and simplex systems, according to Fig. 3, the frequency of source 10 will be higher than 10 that of source 1, as in the embodiments of the invention illustrated, in previous figures, but not high enough to be within audition, and hence, requiring to be modified by the instrument 27, to bring it within audition as 15 described.

The ticker is essentially an instrument having a metallic point dragging over the surface of a rotating metal plate, so that when introduced into an electric circuit, the 20 irregularities on the surface of the plate cause variations in resistance of the circuit, and thus produce variations in the current of sufficiently high rate to make the current effect audible.

25 An oscillating audion is an instrument for generating oscillatory currents whose frequency is determined by the electrical constants of the oscillatory circuit with which it is associated. According to the invention 30 of Messrs. Austin and Cohen, this device is applied to a receiving circuit and made to bring a current below audition up to audition, in the following manner:—

The constants of the oscillating circuit associated with the audion are adjusted to 35 bring the frequency of the oscillation within the range of audibility so that they are heard as a definite note in the telephone, and the effect of the current of the received signals, superimposed upon the normal oscillating current of the oscillating audion, will be to vary the intensity in accordance with the signals and thus render the latter intelligible.

45 While we have shown but a single extra simplex circuit, superimposed upon the duplex system, we desire it understood that our invention is not restricted in its use to single superimposing, but may be made applicable to multiple superimposing of simplex circuits with transmitting equipments either at the same or at opposite ends; this to be accomplished by the proper use of counterbalancing transformers, loop circuits 55 and differences in frequencies employed.

We also desire it understood that it is practicable to have both transmitting and receiving equipments at each end of the superimposed simplex system, and thus use 60 either end as the transmitting station, or receiving station, by merely providing means for cutting the appropriate equipments in and out at will, as for instance, at certain predetermined times, so that simplex sending will be in one direction at one part of

the day, and in the other direction, at another part of the day.

We claim:—

1. The improvement in the art of cable signaling, which consists in superimposing 70 an extra, simplex circuit upon the standard duplex equipment which operates with unbroken alternating current of a frequency below audition and operating this simplex circuit with an unbroken alternating current 75 of different frequency from that employed in the standard duplex system, and modifying the frequency of the simplex system at the receiving end, to render it readily audible and receiving the signals of the simplex 80 circuit by audition.

2. The improvement in the art of cable signaling, which consists in superimposing 85 an extra, simplex circuit upon the standard duplex equipment, operating both said circuits with unbroken alternating currents of frequencies below audition but different from each other, the frequency of the simplex circuit being the higher, superimposing the current of the simplex system, upon an 90 audion circuit which oscillates with an audible frequency, and thereby varying the intensity of the audion current in accordance with the received signals, and receiving the resultant current by telephone. 95

3. A system of multiplex electric signaling comprising a long distance duplex system embodying a line conductor, a source of unbroken alternating current of low frequency, and transmitting and receiving instrumentalities at the respective ends, and a superimposed simplex system embodying a source of unbroken alternating current of a different low frequency which is below audition, a transmitting and a receiving equipment, in circuit with the same line, adapted to send and receive current of different characteristics from that of the duplex system, and in which the receiving equipment is capable of excluding the currents of the duplex system, and means for modifying the frequency of the simplex system at the receiving end to render it readily audible. 100

4. A multiplex system of electric signaling comprising a long distance duplex cable system including a receiving equipment and a source of alternating current of low frequency at each end; and a superimposed simplex system including at one end a source of alternating current of a different frequency which is below audition and at the other end a receiving equipment capable of admitting the current of the simplex system but excluding the current of the duplex system, and comprising means for modifying 115 the frequency of the simplex system to render it readily audible. 120

5. A multiplex system of electric signaling comprising a long distance duplex cable system including a receiving equipment and a 130

- source of alternating current of low frequency at each end; and a superimposed simplex system including at one end a source of alternating current of a different frequency which is below audition and at the other end a receiving equipment capable of admitting the current of the simplex system but excluding the current of the duplex system and comprising means for modifying the frequency of the simplex system to render it readily audible; the receiving equipments of the respective systems, including signaling devices of different classes.
6. A multiplex system of electric signaling comprising a long distance duplex cable system including a receiving equipment and a source of alternating current at each end; and a superimposed simplex system including at one end a source of alternating current of a different frequency which is below audition, and at the other end a receiving equipment capable of admitting the current of the simplex system but excluding the current of the duplex system and comprising means for modifying the frequency of the simplex system to render it readily audible; the several receiving equipments including signaling devices; and the signaling device of the simplex system delivering low frequencies within audition, and the frequencies delivered by the signaling devices of the duplex system being below the limits of audition.
7. A multiplex system of electric signaling comprising a duplex system including a receiving equipment and a source of alternating current at each end; and a superimposed

simplex system including at one end a source of alternating current of different frequency from that of the duplex system, and at the other end a receiving equipment capable of admitting the current of the simplex system but excluding the current of the duplex system; the frequencies of the currents transmitted through the respective systems being below audition, and the receiving equipment of the simplex system including a translating device capable of converting the received energy into frequencies within audition.

8. A multiplex system of electric signaling comprising a duplex system including a receiving equipment and a source of alternating current at each end; and a superimposed simplex system including at one end a source of alternating current of different frequency from that of the duplex system, and at the other end a receiving equipment capable of admitting the current of the simplex system but excluding the current of the duplex system; the current of the simplex system being of lesser magnitude than that of the duplex system, the receiver of the duplex system being responsive only to a current of greater magnitude than that of the simplex system, and the receiver of the simplex system being sensitive to current of such lesser magnitude but tuned to exclude frequencies of the duplex system.

The foregoing specification signed at Washington, in the District of Columbia. 70
